UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CAR-TRUCK.

No. 825,037.

Specification of Letters Patent.

Patented July 3, 1906.

Application filed October 30, 1905. Serial No. 285,144.

To all whom it may concern:

Be it known that I, ETHAN I. DODDS, a citizen of the United States, residing at Pullman, in the county of Cook and State of Illinois, have invented certain new and useful Improvements in Car-Trucks, of which the following is a specification.

Although it is desirable to have all the parts of a railway-car-truck frame integral, the same being made by casting, it has been found that such a structure shrinks unevenly and twists to such an extent as to render its use infeasible. To overcome this difficulty and at the same time make the frame as near integral as is permissible, thereby securing economy in manufacture, rigidity, and strength, I have invented a frame the preferred mechanical embodiment of which comprises two cast-metal side members which are joined together by transoms, the length of which may be varied to compensate for any inequalities in the shrinking of the metal of the sides. These side members have integral inwardly-projecting portions to which the swing-hangers which support the spring-planks are attached, and integral with each of these portions is a safety-beam provided with a recess on its under surface to fit over the adjacent axle.

In the accompanying drawings I have illustrated two embodiments of my invention, like reference characters referring to the same parts throughout.

Figure 1 is a side elevation, partly in longitudinal vertical section, of the preferred embodiment of my invention. Fig. 2 is a plan view of the truck illustrated in Fig. 1. Fig. 3 is a perspective view of one of the side members of the frame of said truck. Fig. 4 is a plan view of a modified form of truck-frame, and Fig. 5 is a perspective view of one of the side members of the frame shown in Fig. 4.

Referring first to Figs. 1, 2, and 3, the truck-frame includes two cast-metal side members 10, of which one is shown in perspective in Fig. 3. The main outer portion of each side member includes a vertical web 11, which joins together top and bottom integral flanges 12 and 13, respectively, which for the greater portion of the length of the side member extend from both sides of web

11. At those points of the frame where the pedestals 14 are attached the web is deflected outwardly, as at 15, to the outer edges of the top and bottom flanges to form vertical surfaces against which the pedestals may be secured. At the points 16, where the web begins its outward deflection, it is somewhat enlarged and provided with vertical apertures 17, through which the securing-bolts of the pedestals are adapted to pass. At its extreme ends 18 web 11 is deflected inwardly to the inner edges of the top and bottom flanges 12 and 13 to form convenient means for attaching angles 19, which secure the end transverse I-beams 20 to the side members, as is shown most clearly in Figs. 2 and 3, corner-plates 19^a being riveted to the top flanges of the side members 10 and I-beams 20. At the points 21 web 11 is enlarged, so that it is of the same width as the bottom flange 13, the enlargements having vertical holes 22, through which pass bolts to secure in place the transverse bars 23, to which are pivoted the swing-hangers, each of which comprises a forked upper portion 24 and an offset depending arm 25.

Extended inwardly from each side member are two integral supporting portions, each having a vertical web 27 and top and bottom flanges 28 and 29, respectively. Each of these webs is enlarged at the point 30, said enlargement having two vertical apertures 31, through which bolts pass to secure in place the swing-hangers 32, as shown in Fig.

1. The lower ends of hangers 25 and 32 are united by the usual lower cross-pins 33, which support the customary spring-plank 34, having the superposed elliptic springs 35, as is usual. Each portion 27 has an integral outwardly-extended safety-beam 36, I shape in section, which is recessed on its under surface at 37 to pass over the car-axle. Straps 38 join the upper flanges of the safety-beams 36 to the lower flanges of the end transoms 20, as is illustrated in Figs. 1 and 2. Channel-beams 39 tie together the two side members, being riveted to webs 27, as shown in Fig. 2. Each side member is also supplied with a plurality of integral equalizing-bar spring-caps 40, with which coöperate the equalizing-springs 41, which rest upon equalizing-bars 42, as is usual.

It should be noted that those portions of the side members which are tied together by the transverse bars 20 and 39 are somewhat lower than the main portions of the side members, this construction being clearly illustrated in Fig. 1.

It will be evident that the inequalities of the cast side members, due to unequal shrinking and warping, may be compensated for wholly or in part by the proper attachment of the transverse bars 20 and 39.

In the modified structure shown in Figs. 4 and 5 the side members are much the same as those illustrated in other figures, except that the safety-beams 43 extend the whole distance from the hanger-supporting portions 27 to the ends of the frame, the ends 44 in this construction being integral with the sides and with the safety-beams. 20 The end portions 44 instead of being united by an I-bar, as shown in Fig. 3, are tied together by the ordinary channel-bar 45.

It should also be noted that in both of these embodiments of my invention the top flanges of the side members are in certain parts, as at 46 and 47, wider than the lower flanges, whereby the structure is strengthened. The top flanges of the safety-beams may be widened at the points of attachment 30 of straps 38, if desired, as shown at 48 in Fig. 2.

This patent is intended to embrace only so much of the disclosure made herein as is covered by the claims.

I claim—

35 1. In a railway-car-truck frame, the combination of two cast-metal side members each having an integral inwardly-projecting portion for supporting a swing-hanger, and a bar attached to and connecting said portions, substantially as described.

45 2. In a railway-car-truck frame, the combination of two cast-metal side members each having an integral inwardly-projecting portion for supporting a swing-hanger, each of said portions having a safety-beam integral therewith, and one or more bars connecting said side members together, substantially as described.

50 3. In a railway-car-truck frame, the combination of two cast-metal side members tied together by transverse bars, each of said members having an I cross-section for a portion of its length and channel-sections at those portions to which the pedestals are attached, substantially as described.

55 4. In a railway-car-truck frame, the combination of two cast-metal side members tied together by transverse bars, each member having a vertical web and integral top and bottom flanges, said web being enlarged at the points where the swing-hanger-supporting bars are attached thereto, substantially as described.

60 5. In a railway-car-truck frame, the com-

bination of two cast-metal side members tied together by transverse bars, each side member having one or more integral equalizing-bar spring-caps, substantially as described.

6. In a railway-car-truck frame, the combination of two cast-metal side members tied together by transverse bars, each side member having a web and top and bottom flanges, said web being enlarged at those portions where the swing-hanger-supporting bars are attached thereto, each side member having a plurality of integral inwardly-projecting portions adapted to support other swing-hangers, said portions having each a web and top and bottom flanges, said webs being enlarged at the points where the swing-hangers are attached thereto, substantially as described.

7. A cast-metal side member for a railway-car truck having laterally-projecting end portions integral with said side member and one or more laterally-extended swing-hanger-supporting portions integral with said side member, substantially as described.

8. A cast-metal side member for a railway-car truck having a laterally-projecting end portion integral with said side member, a laterally-extended portion adapted to support a swing-hanger integral with said side member, and a safety-beam integral with said end and swing-hanger-supporting portions, substantially as described.

9. A cast-metal side member for a railway-car truck having top and bottom marginal flanges, a laterally-projecting end portion with top and bottom flanges integral with said side member, a laterally-extended portion with top and bottom flanges adapted to support a swing-hanger integral with said side member, and a safety-beam with top and bottom flanges and recessed on its under side integral with said end and swing-hanger-supporting portions, substantially as described.

10. In a railway-car-truck frame, the combination of cast-metal side members each having integral therewith laterally-extended end portions and one or more laterally-projecting swing-hanger-supporting portions, and transverse bars attached to and tying together the pairs of corresponding laterally-extended end and swing-hanger-supporting portions, substantially as described.

11. In a railway-car-truck frame, the combination of cast-metal side members each having integral therewith laterally-extended end portions lower than the main portion of the side member and one or more laterally-projecting swing-hanger-supporting portions whose ends are lower than the main portion of the side member, and transverse bars secured to and tying together the corresponding pairs of projecting end and swing-hanger-supporting portions, substantially as described.

12. In a railway-car-truck frame, the combination of cast-metal side members each hav-

ing integral therewith laterally-extended end portions lower than the main part of the side member, one or more laterally-projecting swing-hanger-supporting portions whose ends are lower than the main part of the side member, and safety-beams connecting said swing-hanger-supporting and end portions, and transverse bars secured to and tying together

the corresponding pairs of projecting end and swing-hanger-supporting portions, substantially as described.

ETHAN I. DODDS.
